UNITED STATES PATENT OFFICE.

JOHN H. BALMER, OF MAPLEWOOD, NEW JERSEY.

DESIGN FOR A COMBINATION BATHROOM FIXTURE.

Application filed January 19, 1927. Serial No. 20,428. Term of patent 14 years.

To all whom it may concern:

Be it known that I, JOHN H. BALMER, a citizen of the United States of America, and a resident of Maplewood, in the county of Essex and State of New Jersey, have invented a new, original, and ornamental Design for Combination Bathroom Fixture, of which the following is a specification.

Reference is to be had to the accompanying drawing in which the figure is a perspective view of a combination bathroom fixture showing my new design.

I claim—

The ornamental design for a combination bathroom fixture as shown.

JOHN H. BALMER.
